UNITED STATES PATENT OFFICE

2,589,550

TWO TEMPERATURE REFRIGERATOR

George K. Iwashita, Nutley, N. J., assignor to Admiral Corporation, Chicago, Ill., a corporation of Delaware

Original application July 14, 1943, Serial No. 494,629. Divided and this application June 16, 1950, Serial No. 168,597

4 Claims. (Cl. 62—117.3)

1

This invention relates to refrigerators and particularly refrigerators of the type having two compartments to be maintained at different temperatures. This application is a division of the copending application of George K. Iwashita, Serial No. 494,629, filed July 14, 1943, issued on June 20, 1950, into Patent No. 2,511,851.

The principal object of this invention is to provide an improved two temperature, two compartment refrigerator having a single refrigerant circulating system incorporating no valves to cool the two compartments to different temperatures.

Another object is to provide an improved refrigerator of the two temperature, two compartment type having a refrigerant circulating system adapted to be removably inserted into the refrigerator cabinet.

Another object is to provide an improved refrigerator of the type having a refrigerant circulating system adapted to be removably inserted into a refrigerator cabinet and arranged to cool a eutectic brine tank surrounding a portion of one of the compartments.

Other objects and advantages will become apparent from the following description taken in conjunction with the accompanying drawings wherein:

Fig. 1 is a front elevational view of a refrigerator constructed according to the present invention; and

Fig. 2 is a medial longitudinal sectional view of the refrigerator shown in Fig. 1 and illustrating the arrangement of the refrigerant circulating system and the brine tank in the cabinet.

In the drawing, the reference character 10 indicates generally a refrigerator incorporating the present invention and having a frost chest 12 and a storage compartment 14 disposed immediately therebelow. The frost chest is formed by a liner 16 which is removably secured to a front frame 18. The storage compartment 14 is formed by a liner 20 which is fixed to the frame 18. An outer metallic shell 22 is wrapped around the frame 18 and encloses the liners 16 and 20 and a machinery compartment 24. The upper side of the machinery compartment is defined by a metallic panel 26 which is fastened to the frame 18 and the outer shell 22. The back of the cabinet is closed by a removable panel 28 which is secured to the shell 22 and panel 26 by means of screws 30.

The space between the liners 16 and 20 and between the liners 16 and 20 and the outer shell 22, bottom panel 26 and rear panel 28 is filled with a

2

suitable thermal insulating material 32 such as rock wool, balsa wool and the like.

The front of the cabinet is closed by a door 34 which may be made of spaced sheet metal panels with the space therebetween filled with a thermal insulating material. The door is provided with a deformable gasket 36 on its inner face which seals against the front face of the refrigerator cabinet. The machinery compartment 26 is closed at its forward face by a decorative panel 38.

The compartment 14 formed by the liner 20 is partially surrounded by a spaced sheet metal wall 40 which has its peripheral edge secured in liquid-tight relation by any suitable means to the outer surface of the liner 20. The outer surface of the liner 20 and the sheet metal wall 40, therefore, form a tank 42 which is filled with a eutectic brine.

20 The cooling of the compartments 12 and 14 is accomplished by a refrigerating system 44 which includes a compressor 46, condenser 48 and a pair of series connected evaporators 50 and 52. The inlet to the evaporator 50 is connected to the 25 outlet from the condenser 48 by a capillary tube 54 and the outlet from the condenser 52 leads to an accumulator 56 which in turn is connected by a suction tube 58 to the inlet of the compressor 46. The evaporator 50 is of serpentine form and is secured in heat exchange relation with the outer face of the liner 16. A heat transfer agent having high thermal conductivity, such as metallic Fermagum, a soft non-oxidizing material impregnated with aluminum flakes, graphite and the like may be used to increase the thermal conductivity between the evaporator coil 50 and the liner 16.

30 The liner 16 and its associated tubing is secured in the cabinet by means of a pair of tensioned straps 60 which are secured at their forward ends to the frame 18 and which have their rear ends fastened together by a detachable connector 62. The liner 16 is thus held firmly against the frame 18 but may readily be disconnected therefrom by opening the connector 62.

35 The evaporator coil 52 is secured in heat transfer relation to the outer surface of the sheet metal wall 40 of the brine tank 42 by a clamp or tensioned strap 64 and may be slid up from under the clamp 64 so that the evaporator portions 50 and 52 may be removed from the cabinet with the other parts of the refrigerant circulating system.

40 It is clear that the two compartments 12 and 14 are effectively cooled by the same refrigerating

system. The frost chest 12 is refrigerated by the upper evaporator 50 which is in direct heat exchange relation with the outer surface of the wall of the liner 16. This compartment is maintained at temperatures substantially below freezing for the storage of frozen foods and for the freezing of foods and ice cubes. The lower evaporator 52 is in heat exchange relation with the metal shell 40 of the eutectic brine tank 42. The evaporator 52 maintains brine at a low temperature, and the brine in turn evenly cools the walls of the liner 20, thus maintaining the compartment 14 at a refrigerated temperature above freezing. The difference in sizes of the compartments and the indirect cooling of the compartment 14 through the brine provide a predetermined temperature between the compartments.

The evaporator 50 is removable from the refrigerator cabinet with the liner 16, while the evaporator 52 is detached from beneath the clamp 64 in order to be removed. In removing the refrigerating system from the cabinet, the back panel 28 is taken off and then a portion 66 of the insulation is removed so that access may be had to the removable refrigerant circulating system and tubing. After a sufficient amount of the insulation 66 has been removed, the connector 62 is unfastened and the liner 16 and its associated tubing 50 are removed from the cabinet out through the open back. The tubes 54 and 58 extend down inside the rear wall 28 and pass through a slot 66 in the bottom panel 26, the slot being covered with a plate 68 which is removably secured to the panel 26 by sheet metal screws 70. This plate 68 is removed with tubing. The compressor and condenser are detached from the frame in the machinery compartment 24. The refrigerating system is replaced in the cabinet by reversing these steps.

While but a single embodiment of this invention has been disclosed, it will be apparent that numerous modifications may be made therein without departing from the spirit of the invention, which is to be limited only by the scope of the appended claims.

What is claimed and desired to secure by United States Letters Patent is:

1. A refrigerator comprising a liner which forms a low temperature compartment, a second liner spaced from the first liner which forms a higher temperature compartment, the second liner being partially encompassed by a spaced sheet which forms with the wall of the liner a eutectic brine tank as a secondary refrigerating system, and a primary refrigerant circulating system having an evaporator coil, said primary evaporator coil having a portion in heat absorbing relation with the low temperature compartment liner and another portion in heat absorbing relation with the upper portion of the eutectic brine tank.

2. A refrigerator comprising a liner to form a first compartment, a second liner spaced from said first liner to form a second compartment, said second liner being partially encompassed by a spaced sheet which forms with the wall of said

liner a eutectic brine tank, and a refrigerant circulating system having an evaporator coil, said primary evaporator coil having a first portion in heat absorbing relation with said first liner and another portion in heat absorbing relation with the upper portion of said eutectic brine tank, said evaporator portions being connected in series.

3. A refrigerator comprising a liner to form a first compartment, a second liner spaced from said first liner to form a second compartment, said second compartment being substantially larger than said first compartment, said second liner being partially encompassed by a spaced sheet which forms with the wall of said liner a eutectic brine tank, and a refrigerant circulating system having an evaporator coil, said primary evaporator coil having a first portion in heat absorbing relation with said first liner and another portion in heat absorbing relation with the upper portion of said eutectic brine tank, whereby the temperature in said first compartment is substantially lower than the temperature in said second compartment.

4. A refrigerator comprising a liner to form a first compartment, a second liner spaced from said first liner to form a second compartment, said second compartment being substantially larger than said first compartment, said second liner being partially encompassed by a spaced sheet which forms with the wall of the liner a eutectic brine tank, and a primary refrigerant circulating system having an evaporator coil, said primary evaporator coil having a first portion in heat absorbing relation with said first liner and another portion connected in series with said first portion and in heat absorbing relation with the upper portion of said eutectic brine tank, the relative sizes of the two compartments and the indirect cooling of said second compartment by said second evaporator portion through said brine tank causing the temperature in said first compartment to be substantially lower than the temperature in said second compartment.

GEORGE K. IWASHITA.
